SEQUENCE CONTROL SYSTEM

Clyde E. Stewart, Upper Darby, Pa., assignor to
 General Electric Company, a corporation of New
 York

Application September 16, 1939, Serial No. 295,292

4 Claims. (Cl. 175—320)

My invention relates to sequence control systems and particularly to a system for controlling the energization of a plurality of electroresponsive devices so that the devices are energized in a predetermined sequence in response to successive operations of a control switch and are de-energized in reverse sequence in response to successive operations of a second control switch, and one object of my invention is to provide an improved control system of this type.

My invention will be better understood from the following description when taken in connection with the accompanying drawing the single figure of which diagrammatically illustrates a sequence control system embodying my invention, and its scope will be pointed out in the appended claims.

Referring to the drawing, 1, 2 and 3 represent three electroresponsive devices shown as contactors for respectively short circuiting the resistors R₁, R₂ and R₃ in an electric circuit xy. The devices 1, 2 and 3 are arranged to be energized in the order named in response to successive closures of a control switch 4 and to be de-energized in the reverse order in response to successive closures of a second control switch 5. The electroresponsive devices 1, 2 and 3 have the control relays 1a, 2a and 3a associated therewith, respectively. The sequential energization of the devices 1, 2 and 3 in the order named is accomplished by having the energizing circuit of each device include normally closed contacts of the associated control relay and normally open contacts of the control switch 4 and of the control relay associated with the preceding device in the predetermined sequence and by having each device complete a locking circuit for itself in series with the winding of the associated control relay when the control switch 4 is opened to interrupt the original energizing circuit of a device. For example, the energizing circuit of the electroresponsive device 2 includes the normally closed contacts b of the associated control relay 2a and the normally open contacts a of the control switch 4 and of the control relay 1a associated with the device 1 which precedes device 2 in the predetermined sequence. Similarly, the energizing circuit of the electroresponsive device 3 includes the normally closed contacts d of the associated control relay 3a and the normally open contacts a of the control switch 4 and of the control relay 2a. The energizing circuit of the electroresponsive device 1 includes the normally closed contacts b of the associated control relay 1a and only the normally open contacts

a of the control switch 4 because the device 1 is the first one to be operated in the predetermined sequence.

By closing their respective contacts a, the electroresponsive devices 1, 2 and 3 complete locking circuits for themselves through the windings of the associated control relays. However, each control relay does not become energized until the contacts a of the control switch 4 in the shunt circuit around the control relay winding are opened.

The de-energization of the electroresponsive devices 1, 2 and 3 in the reverse order in response to successive closures of the control switch 5 is effected by having each control relay, when it is energized, prepare for itself in shunt to the winding of the associated electroresponsive device a holding circuit which is arranged to be completed by the closing of the control switch 5 if the control relay associated with the succeeding device in the predetermined sequence is de-energized. For example, the control relay 1a, when energized, prepares through its contacts c and the contacts d of relay 2a a shunt circuit around the winding of electroresponsive device 1 so that if the control switch 5 is closed, when both the device 1 and the control relay 1a are energized and the control relay 2a is de-energized, the device 1 becomes de-energized because of the shunt circuit around its winding. Similarly, the control relay 2a, when energized, prepares through its contacts c and the contacts b of control relay 3a a shunt circuit around the winding of electroresponsive device 2 which can be completed by closing the contacts a of the control switch 5. Control relay 3a, by closing its contacts c, prepares a similar shunt circuit around the winding of the associated electroresponsive device 3.

The operation of the control arrangement shown in the drawing is as follows: For the purpose of describing this operation, it will be assumed that it is desired to energize devices 1 and 2, then de-energize 2, then energize devices 2 and 3 and then de-energize devices 3, 2 and 1 in the order mentioned. This is accomplished by first closing control switch 4 twice, then closing control switch 5 once, then closing control switch 4 twice and then closing control switch 5 three times. The first closure of the contacts a of control switch 4 completes an energizing circuit for device 1 through contacts b of control relay 1a. When the contacts a of control switch 4 are opened after the first closure thereof, a locking circuit for device 1 is energized through con-

5 tacts *a* of device 1 and the winding of the associated control relay 1*a* so that this control relay becomes energized. The second closure of the contacts *a* of the control switch 4 completes an 10 energizing circuit for the electroresponsive device 2 through contacts *b* of control relay 2*a* and contacts *a* of control relay 1*a*. When the contacts *a* of control switch 4 are opened after the second closure thereof, a holding circuit for device 2 is 15 energized through its contacts *a* and the winding of control relay 2*a* so that this control relay becomes energized.

10 The closing of the contacts *a* of control switch 5, when only the devices 1 and 2 are energized, completes a holding circuit for control relay 2*a* through contacts *c* of relay 2*a* and contacts *b* of control relay 3*a* so that the winding of device 2 is shunted and this device becomes de-energized. The subsequent opening of the contacts *a* of the 15 control switch 5 opens the holding circuit of the control relay 2*a* so that it becomes de-energized.

15 The next closure and opening of the contacts *a* of control switch 4 effects the energization of the electroresponsive device 2 and the subsequent 20 energization of the associated control relay 2*a* in the manner above described. The next closure of the contacts *a* of control switch 4, after the control relay 2*a* is re-energized, completes through contacts *a* of relay 2*a* and contacts *d* of control relay 3*a* an energizing circuit for electroresponsive device 3. When the contacts *a* of control switch 4 are opened after the electroresponsive device 3 is energized, a holding circuit 25 is energized for device 3 through its contacts *a* and the winding of the associated control relay 3*a* so that this control relay becomes energized.

30 The closing of the contacts *a* of control switch 5, when all of the devices 1, 2 and 3 are energized, completes a holding circuit for the control relay 3*a* through contacts *c* of relay 3*a* so that the winding of electroresponsive device 3 is shunted and becomes de-energized. The subsequent opening of the contacts *a* of control switch 5 opens the holding circuit of the control relay 3*a* 35 so that it becomes de-energized. The next closure and opening of the contacts *a* of control switch 5 effects the de-energization of the electroresponsive device 2 and its associated control relay 2*a* in the manner above described. The next closure of the contacts *a* of control switch 5 completes a holding circuit for control relay 1*a* through contacts *c* of relay 1*a* and contacts *d* of control relay 2*a* so that the winding of electroresponsive device 1 is shunted and becomes 40 de-energized. The subsequent opening of the contacts *a* of control switch 5 opens the holding circuit of the control relay 1*a* so that it becomes de-energized and all of the control devices are restored to their normal condition.

45 60 While I have, in accordance with the patent statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

65 70 What I claim as new and desire to secure by Letters Patent of the United States is:

75 1. In combination with a plurality of electroresponsive devices and two control switches, an arrangement for energizing said devices in a predetermined order in response to successive operations of one of said control switches and for de-

energizing said devices in the reverse order in response to successive operations of the other control switch including a control relay associated with each of said devices, means for energizing each device except the first to be energized in said predetermined order in response to the operation of said one of said control switches only when the associated control relay is in its normal position and the control relay associated with the preceding device in said predetermined order is in its operated position, means for moving each control relay to its operated position in response to the next restoration of said one of said control switches to its normal position after the associated device has been energized, means for de-energizing each device except the last to be energized in said predetermined order in response to the operation of the other of said control switches only when the associated control relay is in its operated position and the control relay associated with the succeeding device in said predetermined sequence is in its normal position, and means for restoring each control relay to its normal position in response to the next restoration of said other of said control switches to its normal position after the associated device has been de-energized.

2. In combination with a plurality of electroresponsive devices and two control switches, an arrangement for energizing said devices in a predetermined order in response to successive operations of one of said control switches and for de-energizing said devices in the reverse order in response to successive operations of the other control switch including a normally de-energized control relay associated with each of said devices, means for energizing each device except the first to be energized in said predetermined order in response to the operation of said one of said control switches only when the associated control relay is de-energized and the control relay associated with the preceding device in said predetermined order is energized, means for energizing each control relay in response to the next restoration of said one of said control switches to its normal position after the associated device has been energized, means for de-energizing each device except the last to be energized in said predetermined order in response to the operation of the other of said control switches only when the associated control relay is energized and the control relay associated with the succeeding device in said predetermined sequence is de-energized, and means for de-energizing each control relay in response to the next restoration of said other of said control switches to its normal position after the associated device has been de-energized.

3. In combination with a plurality of electroresponsive devices and two control switches, an arrangement for energizing said devices in a predetermined order in response to successive operations of one of said control switches and for de-energizing said devices in the reverse order in response to successive operations of the other control switch including a normally de-energized control relay associated with each device, an energizing circuit for each device except the first to be energized in said predetermined order including normally closed contacts of the associated control relay and normally open contacts of said one of said control switches and of the control relay associated with the preceding device in said predetermined order, a locking circuit for each device including in series therewith

- the winding of the associated control relay, and a locking circuit for each control relay except the one associated with the last device to be energized in said predetermined order including a shunt circuit around the associated device and having in series normally open contacts of said other control switch and normally closed contacts of the control relay associated with the succeeding device in said predetermined sequence.
4. In combination with a plurality of electro-responsive devices and two control switches, an arrangement for energizing said devices in a predetermined order in response to successive operations of one of said control switches and for de-energizing said devices in the reverse order in response to successive operations of the other control switch including a normally de-energized control relay associated with each device, an energizing circuit for each device except the first to be energized in said predetermined order in-
cluding normally closed contacts of the associated control relay and normally open contacts of said one of said control switches and of the control relay associated with the preceding device in said predetermined order, a second energizing circuit for each device in parallel with the other energizing circuit therefor and including in series normally open contacts of the device and the winding of the associated control relay, and a shunt circuit around the winding of each device except the last to be energized in said predetermined order and the normally open contacts thereof in said second energizing circuit thereof including normally closed contacts of the control relay associated with the succeeding device in said predetermined sequence and normally open contacts of the associated control relay and of said other control switch.
